(57) **CLAIM**

(21) Appl. No.: **29/762,697**

The ornamental design for a shelf divider for dividing a shelf or a tray, as shown and described.

(22) Filed: **Dec. 17, 2020**

DESCRIPTION

(51) LOC (13) Cl. **06-06**

FIG. 1 is a top perspective view of the shelf divider for dividing a shelf or a tray showing my new design;

(52) U.S. Cl.
USPC **D6/706**

FIG. 2 is a bottom perspective view thereof;

(58) **Field of Classification Search**

FIG. 3 is a top view thereof;

USPC D6/706, 332, 512, 705.7, 329, 574;
D8/380, 381, 349; D25/120, 126;
108/60; 312/348.3; 211/153, 184, 183,
211/59.1, 59.2, 86.01, 90.01, 175

FIG. 4 is a bottom view thereof;

CPC A47F 5/005; A47F 5/0068; A47F 5/0043;
A47B 57/58; A47B 57/583; A47B 57/585

FIG. 5 is a front view thereof;

See application file for complete search history.

FIG. 6 is a back view thereof;

(56) **References Cited**

FIG. 7 is a right side view thereof;

U.S. PATENT DOCUMENTS

FIG. 8 is a left side view thereof; and,

D707,994 S * 7/2014 Le D6/706
D760,519 S * 7/2016 Le D6/706

FIG. 9 is a front perspective view thereof, the shelf divider shown in use.

In the figures, features shown by broken lines are for illustrative purposes only and form no part of the claimed design. Certain solid lines of varying length indicate surface shading and the lines themselves form no part of the claimed design.
